UNITED STATES PATENT OFFICE.

DEAN C. LAWSON, OF EAST ROCHESTER, NEW YORK.

HOOK.

1,325,202.

Specification of Letters Patent.

Patented Dec. 16, 1919.

Original application filed February 23, 1915, Serial No. 10,127. Divided and this application filed October 12, 1916. Serial No. 125,318.

To all whom it may concern:

Be it known that I, DEAN C. LAWSON, a citizen of the United States, residing at East Rochester, in the county of Monroe and State 5 of New York, have invented certain new and useful Improvements in Hooks, of which the following is a specification.

This application is a division of my previous application No. 10127 filed February 10 23rd, 1915.

The object of my invention is to provide a new and improved form of combination coat and hat hook.

This and other objects of the invention will 15 be fully illustrated in the drawings, described in the specification and pointed out in the claims at the end thereof.

In the drawings,

Figure 1 is a side elevation of one of my 20 improved hooks.

Figs. 2 and 3 are detail views of modifications of the end of the hook.

In the accompanying drawings like reference numerals indicate like parts.

25 As shown in Fig. 1, the hook is made preferably as a casting having a back 1 with a screw shank 2 by which it is adapted to engage the wall. It also comprises the downwardly and outwardly curved portions 3 on which coats may be hung and the upwardly and downwardly curved portion 4 which is intended to hold hats suspended therefrom.

35 On the outer end of the upwardly curved portion the hook is bent, first up and then down forming a reentrant curve or angle with the portion 4. Fastened to the end side of the reentrant angle of the hook is a spring clamping device 5 which presses forward 40 against the downwardly turned end 6 of the hook and between the spring and the end 5 the rim of a hat may be clamped so that the hat will hang suspended therefrom. The lower end of the spring 5 is turned up 45 to form a handle by which it may be moved.

The reentrant angle may also be formed with a pivot joint 7 in which is suspended a dog 8 which is pressed forwardly by the spring 9 so that the forward end 10 of the 50 dog will press against the downwardly turned end 11 of the hook. The rear end 12

of the dog serves as a handle by which it may be drawn backward.

The spring clamp may be fastened on the outside of the downwardly turned end of the 55 hook, in which case it will consist of the clamping plate 13, pivoted at 14, pressed downwardly at the upper end by the spring 15 and bearing against the downturned end 16 at the bottom thereof so that between the 60 plate 13 and the downturned end 16 the rim of the hat may be clamped and the hat suspended thereby.

It will also be noticed that the downturned end of the tip in Figs. 1 and 3 is 65 bowed outwardly above the lower end of the tip and the clamping device curves inwardly. This leaves ample room or clearance for the rim of a hat if the rim is extra thick as in the case of Derby hats.

In Fig. 2 this clearance is provided in the shape of the clamping device which bears against a straight downwardly turned end. The hook is used to suspend a hat by drawing the clamping device back and inserting 75 the rim of the hat and then releasing the clamping device which will then engage the rim and hold the hat suspended.

I claim—

1. A hook having a shank curved upwardly and outwardly, the tip of which is bent upwardly and downwardly, a spring 80 pressed clamping device fastened on the under side of the tip and pressing forward against the downturned end of the tip, the tip of said hook having a rounded surface on the top thereof.

2. A hook having a shank curved upwardly and outwardly, the tip of which is bent upwardly and downwardly, a spring 90 pressed clamping device fastened on the under side of the tip and pressing forward against the downturned end of the tip, said downturned end of the tip being bowed outwardly away from said clamping device 95 above the lower end thereof.

In testimony whereof I affix my signature in presence of a witness.

DEAN C. LAWSON.
